United States Patent

Des. 236,472
Patented Aug. 26, 1975

236,472

INCINERATOR

Seth R. Banks, Milwaukee, Wis., assignor to
Raytheon Company

Filed Aug. 7, 1974, Ser. No. 495,342

Term of patent 14 years

Int. Cl. D23—99

U.S. Cl. D23—85

FIG. 1

FIG. 2

FIG. 3

FIG. 4

FIG. 1 is an isometric view showing the top, front and one side of an incinerator embodying the invention;

FIG. 2 is a front elevational view of the incinerator shown in FIG. 1;

FIG. 3 is an elevational view of the opposite side of the incinerator shown in FIG. 1; and

FIG. 4 is a rear elevational view of the incinerator shown in FIG. 1.

I claim:

The ornamental design for an incinerator, as shown.
